DESIGN FOR AN AMPULE

Arthur E. Smith, Los Angeles, Calif.

Application April 10, 1936, Serial No. 62,046

Term of patent 7 years

To all whom it may concern:

Be it known that I, Arthur E. Smith, a citizen of the United States and residing at Los Angeles, in the county of Los Angeles and State of California, have invented a new, original, and ornamental Design for an Ampule, of which the following is a specification, reference being had to the accompanying drawing forming a part thereof.

In the accompanying drawing, Fig. 1 is an elevation of an ampule showing my new design; Fig. 2 is a front view; and Fig. 3 is a rear view.

I claim:

The ornamental design for an ampule substantially as shown.

ARTHUR E. SMITH.
